UNITED STATES PATENT OFFICE.

EMIL DREHER, OF NEW YORK, N. Y.

MAGAZINE FIRE-ARM.

SPECIFICATION forming part of Letters Patent No. 465,248, dated December 15, 1891.

Application filed June 18, 1891. Serial No. 396,674. (No model.)

To all whom it may concern:

Be it known that I, EMIL DREHER, a citizen of the United States, and a resident of the city of New York, in the county of New York and State of New York, have invented certain new and useful Improvements in Magazine Fire-Arms, of which the following is a specification.

This invention relates to a magazine fire-arm; and the object of my invention is to provide a fire-arm of this kind in which a considerable number of cartridges can be placed into a magazine, the said magazine readily introduced into the gun and the cartridges successively fed into the firing-chamber and withdrawn after being discharged, the empty shells being forced back into the magazine and the filled shells being forced by the empty shells into position to be introduced into the firing-chamber.

The invention consists in a gun provided with a chamber behind the breech end of the barrel, which chamber is adapted to receive a cartridge-magazine, U-shaped in cross-section, the chamber containing a sleeve adapted to be operated from the breech-bolt, said sleeve being provided with a pusher, which pushes the empty cartridges when withdrawn from the barrel into the top opening at one side of the U-shaped magazine, and thereby forces out a cartridge at the opposite side of the magazine, which cartridge is pushed by the breech-bolt into the firing-chamber of the gun by the return movement of said breech-bolt.

The invention also consists in the construction and combination of parts and details, which will be fully described hereinafter, and finally pointed out in the claims.

In the accompanying drawings, Figure 1 is a vertical longitudinal section of the breech part of my improved machine fire-arm, showing the breech-bolt withdrawn and a cartridge in position to be introduced into the firing-chamber. Fig. 2 is a similar view showing the breech-bolt pushed home and the cartridge introduced ready for firing. Fig. 3 is a top view of the cartridge-support and the pusher for pressing the empty cartridge back in the magazine. Fig. 4 is a side view of the

same, parts being broken out and others in section. Figs. 5, 6, and 7 are top views of the cartridge support and shifter, the magazine being shown in section. Fig. 8 is an end view of the magazine. Fig. 9 is a vertical transverse sectional view of the same. Fig. 10 is a longitudinal sectional view of the same, and Fig. 11 is a vertical transverse sectional view through the breech part of the gun on the line 11 11 of Fig. 1.

Similar letters of reference indicate corresponding parts.

The gun is provided at the breech end of the barrel M with a chamber A, adapted to receive the magazine B, said chamber having an opening on the under side of the gun, through which opening the magazine can be introduced. A pivoted latch C, adapted to swing laterally, serves for locking the magazine in the chamber A; but it is evident that any other kind of locking device may be substituted for the latch C. Through the top of the chamber A the sliding breech-bolt D passes, which may be of any approved construction, as the construction of the breech-bolt, firing-pin, &c., is immaterial. The breech-bolt is provided on its front edge with a cartridge-extractor D', of any approved construction, that slides in a groove D''. In the center of the chamber A a rod E is arranged longitudinally and is suitably fixed in the ends of the chamber. Said rod E is surrounded by a loose sleeve F, adapted to turn on the same. The sleeve F is provided at the opposite ends with oppositely-inclined ridges G G', on which the pin H can act, that projects downward from the front end of the breech-bolt D. A curved spring-arm or cartridge-pusher J projects upward from the sleeve F, at or near the rear end of the same, said curved spring-arm projecting upward between two curved rods K K, which form a support for the cartridge m, about to be pushed into the firing-chamber. Instead of mounting the sleeve F to rotate on the rod E, it may be mounted to turn on two short pivots or trunnions projecting from the ends of the chamber A.

The magazine consists of a box which is approximately U-shaped in cross-section, and is made of sheet metal and provided with the

outer wall *a* and the inner wall *b*, both **U**-shaped, which walls are secured to the end piece *d* and the transverse partition *e*, arranged a short distance from one end of the 5 magazine, both said end piece *d* and partition *e* being **U**-shaped. The upper edges *a'* of the outer wall *a* are extended upward and curved toward each other, and the upper edges of the inner wall *b* are a short distance below the 10 upper edges of the outer wall *a* to form the longitudinal openings *f*, through which the cartridges can pass into and out of the **U**-shaped compartment in the magazine. To the outer wall *a* a curved spring *g* is secured 15 at each side, so as to project over the uppermost cartridges, as shown, for the purpose of holding the same in the magazine and preventing the cartridges from dropping out while the magazine is being taken from the 20 cartridge-box or magazine-box and introduced into the chamber.

The operation is as follows: After the last cartridge *m* has been fired the latch *C* is opened, so as to permit the magazine *B* to 25 drop out of the chamber *A*, said magazine containing ten empty shells. A filled magazine is placed into the chamber *A* and the latch *C* is replaced, when the gun is again ready for firing. As the breech-bolt is with- 30 drawn to cock the gun, the extractor *D'* withdraws the empty shell from the firing-chamber of the barrel, and when said shell is entirely withdrawn from the firing-chamber, and rests solely upon the supports *K*, the pin *H* strikes the forward end of the curved ridge *G* on the sleeve *F*, and by acting on the same turns the sleeve *F* and moves the finger *J* in the direction of the arrow *x'*, Figs. 3 and 5, and said finger pushes the empty shell from 35 the supports *K* in the left-hand top opening of the magazine and presses it down in said left-hand compartment of the magazine, (see Fig. 6,) the pressure upon this empty shell exerting a pressure on the remaining shells 40 or cartridges in the magazine, whereby the uppermost cartridge in the right-hand compartment of the magazine is pressed out of the top of said right-hand compartment and passes upon the two guards or rods *K*. (See 45 Fig. 7.) As the breech-bolt *D* is pushed forward, it pushes the cartridge resting on the supports *K* in the direction toward the firing-chamber and into said firing-chamber. Just before the bolt has completed its forward 50 stroke it acts on the side of the inclined ridge *G'* on the forward end of the sleeve *F* and turns the sleeve in the inverse direction of the arrow *x'*, the spring-arm *J* sliding along the under side of the breech-bolt and snap- 55 ping under it to the other side of the same. The gun is cocked automatically in the usual manner by withdrawing the breech-bolt, and when the breech-bolt has been pushed forward to drive the cartridge into the firing-chamber the gun is ready to be fired. The 60 shell of the cartridge just discharged is then again withdrawn by pulling the breech-bolt 65

toward the rear, and when the breech-bolt is almost entirely withdrawn and said empty shell rests upon the supports *K* the sleeve *F* 70 is again turned in the direction of the arrow *x'*, Fig. 3, and the empty shell forced into the top of the left-hand compartment of the magazine, and thereby a cartridge forced out of the top of the right-hand compartment of 75 the magazine, and upon the supports *K* the breech-bolt is pushed forward, and when it has about completed its forward stroke it turns the sleeve *F* in the inverse direction of the arrow *x'*, and so on. 80

The magazine is adapted to hold ten thirty-caliber cartridges. By enlarging the chamber and magazine the same can be adapted to hold a greater number of cartridges. The magazine and shells therein can be collected 85 by the soldiers to be refilled, or, in case of an emergency or of war they can be dropped when taken from the gun. The magazines are very inexpensive, as they are made of plain sheet metal. 90

Having thus described my invention, I claim as new and desire to secure by Letters Patent—

1. In a gun, the combination, with a barrel and a chamber at the breech end of the 95 same, of a sleeve mounted in said chamber, a breech-closing mechanism, mechanism operated by said breech-closing mechanism for rotating said sleeve, and of a cartridge-pusher on said sleeve, substantially as set forth.

2. In a gun, the combination, with a barrel, a sliding breech-bolt, and a chamber in which said breech-bolt can slide, of a rotating sleeve in the chamber, a cartridge-pusher on 105 said sleeve, means for operating the sleeve from the breech-bolt, and a cartridge-support above said sleeve, substantially as set forth.

3. In a gun, the combination, with a barrel, breech-bolt, and a chamber at the breech end of the barrel, of a sleeve mounted to turn in said chamber and provided with a cartridge-pusher, means for operating said sleeve from the breech-bolt, and a cartridge-support 115 formed of two rods or wires above the sleeve, substantially as set forth.

4. In a gun, the combination, with a barrel, a sliding breech-bolt, and a chamber, of a rotative sleeve in the chamber, which sleeve 120 has oppositely-inclined ridges at the ends, a cartridge-pusher projecting from said sleeve, and a pin projecting from the breech-bolt and adapted to act on said inclined ridges of the sleeve, substantially as set forth. 125

5. In a gun, the combination, with a barrel, breech-bolt, and a chamber at the breech end of the barrel, which chamber is adapted to receive a magazine, of a sleeve in said chamber, mechanism for turning said sleeve 130 from the breech-bolt, a cartridge-pusher on said sleeve, and a latch for holding the magazine in place in the chamber, substantially as set forth.

6. In a gun, the combination, with a barrel, sliding breech-bolt, and a chamber at the breech end of the barrel, of a **U**-shaped cartridge-magazine adapted to be placed in said chamber, and mechanism operated from the breech-bolt for pressing the empty shells into said magazine, substantially as set forth.

In testimony that I claim the foregoing as my invention I have signed my name in presence of two subscribing witnesses.

EMIL DREHER.
